UNITED STATES PATENT OFFICE.

WILLIAM E. WOODARD, OF LIMA, OHIO.

LOCOMOTIVE CUT-OFF INDICATOR.

Application filed January 31, 1920. Serial No. 355,393.

To all whom it may concern:

Be it known that I, WILLIAM E. WOODARD, a citizen of the United States, residing at Lima, in the county of Allen and State of Ohio, have invented certain new and useful Improvements in Locomotive Cut-off Indicators, of which the following is a specification.

This invention relates to cut-off indicator mechanism for locomotives, and it is a continuation in part of my issued patent No. 1,341,961, dated June 1, 1920, entitled Locomotives and methods of operating the same.

In the operation of standard types of steam locomotives and also locomotives such as illustrated in the aforesaid application, the engineman shortens or lengthens the cut-off in accordance with his best judgment of the conditions of the fire, steam pressure, speed, etc. There is a well defined and established rate at which the cut-off should be shortened or lengthened to obtain the maximum power of the locomotive at all times and this can be calculated in advance by a mechanical engineer familiar with the art. It can however only be approximated when the cut-off is lengthened or shortened in accordance with the judgment of the engineman and the degree of efficiency obtained is dependent on his skill.

I propose to provide improved means for positively indicating the point of cut-off designed to obtain the maximum efficiency and in the accompanying drawings I have illustrated various embodiments of my invention in preferred form. Of the drawings

Figure 1 is a diagrammatic view of a locomotive such as shown in the aforesaid application with my improvements applied thereto; Figure 2 is an enlarged side elevation of the reverse lever of Figure 1 with my improvements applied thereto; Figure 3 is a plan view of a detail of my invention; Figure 4 is a plan view of a modification of such detail; Figure 5 is side elevation of a modification of my improvements; Figure 6 is an end elevation of Figure 5 partly in section; Figure 7 is a side elevation of still another modification of my invention; Figure 8 is a side elevation of a reverse lever and a speed operated device embodying another modification of my invention; and Fig. 9 is an end elevation of Fig. 8, shown partially in section.

For a detailed description of the locomo-

tive shown in Figure 1, attention is directed to the aforesaid copending application, and it will suffice for the purposes of this specification to say that the locomotive is equipped with a forward group of cylinders B and a rear group C, the combined normal maximum horsepower output of which is greater than the boiler capacity in order to utilize the excess capacity of the boiler in the zone below the point at which the normal horsepower developed by the leading group approximates the boiler capacity. Each group of cylinders is provided with a valve motion D, operated by power reverse mechanism, such mechanism being so arranged that the cut-offs are shortened differentially, that is to say the cut-off for the rear group is shortened at a faster rate than the cut-off for the forward group, in such manner as to keep the combined horsepower output of both groups of cylinders within the boiler capacity at all operating speeds.

The cut-off indicator mechanism comprises a speed operated device such, for example, as a speed indicator E, the shaft 7 of which is driven from an axle or wheel in any preferred manner; the case 8 secured to the quadrant 9 and provided with a plurality of lights 10, such lights being arranged in two rows with the lights of one row staggered with respect to the lights of the other row; the battery 11; and the wiring 12. Any suitable arrangement of wiring may be employed, but I prefer to have the positive from the battery lead to the pointer 13 of the speed device, the dial of which is provided with a plurality of contacts from each of which a separate wire 95 leads to the respective lights 10 in the case 8, the circuit being completed by the return to the battery. Several of such separate wires are shown in dotted lines in Fig. 2. Where the speed device is an indicator, the dial may be graduated in any preferred manner as for example in increments of five miles per hour, with the contacts located opposite the graduations. When the pointer 13 engages with one of the contacts, the circuit is completed for the respective light and the engineman is apprized thereby to what point he should shift the reverse lever 14. In Figure 4, I have shown the case 8 as being provided with but one row of lights 10.

In the construction shown in Figures 5

and 6, instead of having an electrically operated signal, I provide a pointer 15 secured to the shaft 16 of the speed device E so as to rotate therewith. The shaft 16 passes through a bushing 17 carried by the quadrant 9 and the reverse lever 14 is rotatably carried on the bushing 17. The engineman is apprized by the pointer of the notch to which he should shift his reverse lever, the position 10 of the pointer being dependent upon the speed of the locomotive.

In the construction shown in Figure 7, the pointer or indicator arm 15 is arranged so as to release the latch 18 of the reverse lever so that the pointer will shift the lever to the desired notch, if the engineman should be neglectful. For both the forward and back motion a pair of indicator arms or pointers, such as shown in Figure 8, may be employed, by connecting both pointers to a common block 19, slideable in a groove 20, the pointers being connected to the block by the links 21. By this arrangement movement is imparted to the pointers in like degree but in the reverse direction.

I claim:

1. An automatic cut-off indicator for locomotives comprising the combination with a reverse lever, of a speed operated device, a cut-off indicator adjacent the lever, and an

operating connection between the speed device and the cut-off indicator, whereby said indicator automatically indicates the point to which the lever should be shifted.

2. An automatic cut-off indicator for locomotives comprising the combination with a reverse lever of a speed operated device, a plurality of indicator lights adjacent the lever and means whereby the speed device completes the circuit of said lights.

3. An automatic cut-off indicator for locomotives comprising the combination with a reverse lever and its quadrant, of a speed operated device, a cut-off indicator adjacent the reverse lever quadrant, and a direct operating connection between the speed device and the indicator for operating the latter to indicate at the quadrant the location to which the lever should be shifted.

4. An automatic cut-off indicator for locomotives comprising the combination with a reverse lever and its quadrant of a cut-off indicator adjacent the quadrant, and means for automatically operating said indicator in accordance with working conditions of the locomotive, to indicate at the quadrant the location to which the lever should be shifted.

In testimony whereof I have heretunto signed my name.

WILLIAM E. WOODWARD,
